HEAT PUMPS

Rodney F. Lauer, Staunton, Va., assignor to Westinghouse Electric Corporation, East Pittsburgh, Pa., a corporation of Pennsylvania

Filed Sept. 18, 1963, Ser. No. 309,677
6 Claims. (Cl. 62—155)

This invention relates to heat pumps that are used for cooling or heating indoor air.

A heat pump used for cooling or heating indoor air usually includes a refrigerant compressor that is connected through a refrigerant reversal valve to indoor and outdoor heat exchange coils. When indoor air heating is required, the reversal valve is adjusted to route discharge gas from the compressor into the indoor coil operating as a condenser, from which refrigerant liquid is supplied through expansion means into the outdoor coil operating as an evaporator. When indoor air cooling is required, the reversal valve is adjusted to route the discharge gas from the compressor into the outdoor coil operating as a condenser, from which refrigerant liquid is supplied through expansion means into the indoor coil operating as an evaporator.

When the reversal valve of such a heat pump is adjusted from one position to the other, at the instant of reversal, the compressor suction is applied to the high pressure coil that has been operating as a condenser, and the high pressure refrigerant from the latter discharges through the compressor into the low pressure coil that has been operating as an evaporator. This creates undesired noise, may damage the valves of the compressor, and liquid from the high pressure coil passes into the compressor, diluting its lubricant, and causing increased wear of the compressor components.

In a widely used heat pump, a heat thermostat, when it calls for indoor air heating, starts the compressor, and energizes a solenoid which adjusts the reversal valve of the heat pump to its air heating position. When the heat thermostat is satisfied, it deenergizes the solenoid of the reversal valve which then adjusts the reversal valve to its indoor air cooling position. A cool thermostat cycles the compressor during air cooling operation.

When such a heat pump is operating to heat indoor air with its outdoor coil operating as an evaporator, low outdoor temperatures may cause frost to form on the outdoor coil, and to melt such frost, it is the practice to use a pressurestat responsive to air pressure drop through the outdoor coil caused by the frost, to adjust the reversal valve to its indoor air cooling position so as to operate the outdoor coil as a condenser for melting the frost. Then, when the frost has melted, a control responsive to the rise in refrigerant pressure within the outdoor coil caused by the melting of the frost, adjusts the reversal valve back to its indoor air heating position.

Thus, in such a heat pump, a reversal valve is adjusted to reverse the flow of refrigerant each time the heat thermostat cycles, and when defrosting of the outdoor coil is started and stopped.

This invention prevents the refrigerant from a high pressure coil from flowing through the compressor into a low pressure coil when the flow of refrigerant is reversed, by placing a by-pass across the refrigerant expansion means between the coils, and opening this by-pass just before reversal takes place, so that when the reversal does take place, the refrigerant from the high pressure coil flows through the by-pass into the low pressure coil instead of through the compressor into the low pressure coil.

An object of this invention is to prevent refrigerant from flowing from a high pressure coil through a

2

refrigerant compressor into a low pressure coil when the flow of refrigerant is reversed.

This invention will now be described with reference to the annexed drawings, of which:

FIG. 1 is a refrigerant circuit of a heat pump embodying this invention;

FIG. 1a is a diagrammatic view of one of the time delay relays used;

FIG. 1b is a diagrammatic view of a defrost relay used;

FIG. 1c is a diagrammatic view of one of the motor starters;

FIG. 1d is a diagrammatic view of another motor starter;

FIG. 1e is a diagrammatic view of a fan relay used;

FIG. 1f is a diagrammatic view of a by-pass valve relay used;

FIG. 1g is a diagrammatic view of another time delay relay used;

FIG. 1h is a diagrammatic view of still another time delay used, and

FIG. 2 is the electrical control circuit of the heat pump.

The discharge side of a conventional, hermetic, refrigerant compressor C, driven by an electric motor CM, is connected by discharge tube 10 to a conventional reversal valve RV which is connected by tube 11 to outdoor coil 12, and by tube 13 to indoor coil 14. The coils 12 and 14 are connected by capillary tube 16 serving as a two-way expansion means, connected in series with a restrictor valve 17 used for reducing the refrigerant volume during air heating operation as disclosed in the G. L. Biehn Patent No. 2,785,540. A by-pass tube 19 is connected to the coils 12 and 14 across the series connection of the valve 17 and the capillary tube 16, and contains a normally closed by-pass valve BPV. The reversal valve RV is connected by suction gas tube 22 to the suction side of the compressor C, through the motor CM as is usual in hermetic compressors.

The reversal valve RV is connected at its ends through capillary tubes 23 and 24 to a pilot valve 25 which is connected by capillary tube 26 to the discharge gas tube 10. The pilot valve 25 is adjusted by a solenoid RVSOL to route discharge gas to one side of or the other side of a piston which is not shown, for moving the piston in opposite directions for adjusting the valve RV to indoor air cooling or indoor air heating positions. When the solenoid RVSOL is energized, it adjusts the valve RV to its air heating position, and when the solenoid RVSOL is de-energized, it adjusts the valve RV to its air cooling position.

A fan OF driven by an electric motor OFM moves outdoor air through the outdoor coil 12.

The compressor motor CM is connected through parallel connected switches 1MSS and 2MSS of motor starters 1MS and 2MS respectively, to electric supply lines L1 and L2. The fan motor OFM is connected through switch OFRS of outdoor fan relay OFR to the supply lines. The motor starter 1MS is connected through switch CTS1 of cool thermostat CT to the supply lines. The fan relay OFR is connected through series connected switch CTS2 of the cool thermostat CT, and normally closed switch DRS1 of defrost relay DR to the supply lines. The reversal valve solenoid RVSOL is connected in series with normally open switch 1TDRS1 of thermal time delay means such as relay 1TDR to the supply lines. The motor starter 2MS is connected in series with parallel connected switches 1TDRS2 of the relay 1TDR and DRS4 of the defrost relay DR to the supply lines.

The relay 1TDR has a heater resistor 30 connected in parallel with by-pass valve relay BPVR and in series with normally closed switch DRS3 of the defrost relay DR

to the supply lines. When the resistor 30 is energized, time is required for it to heat and cause its switches 1TDRS1 and 1TDRS2 to warp closed, and when the resistor 30 is deenergized, time is required for it to cool and the switches 1TDRS1 and 1TDRS2 to warp open.

Time delay means such as delay relay 2TDR has an electromagnetic winding 2TDRW connected through normally closed switch BPVRS1 of the by-pass valve relay BPVR to the supply lines; has normally closed switches 2TDRS1 and 2TDRS3, and has a switch 2TDRS2 which responds to heat from heater resistor 40, and which warps open when the resistor 40 is heated. The resistor 40 is connected through the normally closed switch 2TDRS3 to the supply lines.

A time delay means such as relay 3TDR, similar to the relay 2TDR, has an electromagnetic winding 3TDRW connected through normally open switch BPVRS2 of the bypass relay BPVR to the supply lines; has normally open switches 3TDRS1 and 3TDRS3, and has a normally closed switch 3TDRS2 which responds to heat from heater resistor 50, and which warps open when the resistor 50 is deenergized and has cooled. The resistor 50 is connected through the switch 3TDRS3 to the supply lines.

The by-pass valve solenoid BPVSOL is connected through series connected switches 2TDRS1 and 2TDRS2 to the supply lines, and is also connected through series connected switches 3TDRS1 and 3TDRS2 to the supply lines.

The defrost relay DR is connected in series with normally closed switch DLCS of the defrost limit control DLC, and parallel connected switches DCS of defrost control DC, and DRS2 of the defrost relay DR.

The defrost control DC is a conventional defrost initiating control which responds to air pressure drop across the outdoor coil 12 caused by formation of frost thereon. The defrost limit control DLC is a conventional control which responds to refrigerant pressure within the outdoor coil 12.

Air cooling operation

When air cooling is required, the heat thermostat HT is off, and the reversal valve RV is in its air cooling position. The cool thermostat CT closes its switches CTS1 and CTS2. The closed switch CTS1 energizes the motor starter 1MS which closes its switch 1MSS which starts the compressor motor CM. The closed switch CTS2 energizes the fan relay OFR through the normally closed switch DRS1 of the defrost relay DR. The energized relay OFR closes its switch OFRS, starting the fan motor OFM. At this time, the by-pass valve solenoid BPVSOL is deenergized, and the by-pass valve BPV is closed. Discharge gas flows from the compressor C through the discharge gas tube 10, the reversal valve RV and the tube 11 into the outdoor coil 12 operating as a condenser. Liquid from the coil 12 flows through the capillary tube 16 and the restrictor valve 17 into the indoor coil 14 operating as an evaporator. Gas from the coil 14 flows through the tube 13, the reversal valve RV and the suction tube 22 to the suction side of the compressor C. The cool thermostat CT cycles the compressor motor CM and the outdoor fan motor OFM.

There would be one or more indoor air fans associated with the indoor coil 14, but since their operation is not affected by this invention, they are not shown.

Air heating operation

When indoor air heating is required, the cool thermostat CT is, of course, off. When the heat thermostat HT calls for heat, it closes its switches HTS1 and HTS2. The closed switch HTS1 energizes the fan relay OFR through the normally closed switch DRS1 of the defrost relay DR. The relay OFR closes its switch OFRS starting the fan motor OFM. The closed switch HTS2 energizes the heater resistor 30 of the time delay relay

70
75
77

79

1TDR, and the by-pass valve relay BPVR through the normally closed switch DRS3 of the defrost relay DR. The relay BPVR opens its switch BPVRS1 and closes its switch BPVRS2. The now open switch BPVRS1 deenergizes the winding 2TDRW of the time delay relay 2TDR which opens its switches 2TDRS1 and 2TDRS3, the latter deenergizing the heater resistor 40 which cools and permits the switch 2TDRS2 to warp closed. The switch 2TDRS2 is not used at this time, and is used when the thermostat HT is satisfied as will be described later. The now closed switch BPVRS2 energizes the winding 3TDRW of the time delay relay 3TDR which closes its switches 3TDRS1 and 3TDRS3. The now closed switch 3TDRS1 energizes the by-pass valve solenoid BPVSOL through the closed switch 3TDRS2 of the time delay relay 3TDR. The solenoid BPVSOL opens the by-pass valve BPV, permitting high pressure gas from the outdoor coil 12 which has been operating as a condenser, to flow through the by-pass tube 19 into the indoor coil 14 which has been operating as an evaporator. The now closed switch 3TDRS3 energizes the heater resistor 50 of the relay 3TDR, which heats and after a period of time, causes the switch 3TDRS2 to warp open and to deenergize the solenoid BPVSOL which closes the by-pass valve BPV.

After a period of time sufficient for the by-pass valve BPV to have opened and closed as described, the switches 1TDRS1 and 1TDRS2 of the time delay relay 1TDR are warped closed by heat from their energized heater resistor 30. The now closed switch 1TDRS1 energizes the reversal valve solenoid RVSOL which adjusts the reversal valve RV to its air heating position. At the same time, the now closed switch 1TDRS2 energizes the motor starter 2MS which closes its switch 2MSS, starting the compressor motor CM. Discharge gas from the compressor C flows through the discharge gas tube 10, the reversal valve RV and the tube 13 into the indoor coil 14 operating as a condenser. Liquid from the coil 14 flows through the capillary tube 16 and the restrictor valve 17 into the outdoor coil 12 operating as an evaporator. Gas from the coil 12 flows through the tube 11, the reversal valve RV and the suction gas tube 22 to the suction side of the compressor C.

When the heat thermostat HT is satisfied, it opens its switches HTS1 and HTS2. The now open switch HTS1 deenergizes the fan relay OFR which opens its switch OFRS, stopping the fan motor OFM. The now open switch HTS2 deenergizes the heater resistor 30 of the time delay relay 1TDR, and the by-pass valve relay BPVR. The relay BPVR opens its switch BPVRS2 and closes its switch BPVRS1. The now open switch BPVRS2 deenergizes the winding 3TDRW of the time delay relay 3TDR which opens its switches 3TDRS1 and 3TDRS3. The now open switch 3TDRS3 deenergizes the heater resistor 50 which cools and causes the switch 3TDRS2 to warp closed, but since the switch 3TDRS1 is now open, the by-pass valve solenoid BPVSOL cannot be energized through the closed switch 3TDRS2. The now closed switch BPVRS1 of the by-pass valve relay BPVR energizes the winding 2TDRW of the time delay relay 2TDR which closes its switches 2TDRS1 and 2TDRS3. The now closed switch 2TDRS1 of the time delay relay 2TDR energizes the by-pass valve solenoid BPVSOL through the closed switch 2TDRS2. The solenoid BPVSOL opens the by-pass valve BPV, permitting high pressure gas from the indoor coil 14 which has been operating as a condenser, to flow through the by-pass tube 19 into the outdoor coil 12 which has been operating as an evaporator. The now closed switch 2TDRS3 energizes the heater resistor 40 of the relay 2TDR. The resistor 40 heats sufficiently after a period of time to cause the switch 2TDRS2 to warp open and deenergize the solenoid BPVSOL which closes the by-pass valve BPV.

After a period of time sufficient for the by-pass valve BPV to have opened and closed as described, the switches 1TDRS1 and 1TDRS2 associated with the now deener-

gized heater resistor 30 of the time delay relay 1TDR warp open. The now open switch 1TDRS1 deenergizes the reversal valve solenoid RVSOL which adjusts the reversal valve RV to its air cooling position. The now open switch 1TDRS2 deenergizes the motor starter 2MS which opens its switch 2MSS, stopping the compressor motor CM.

Defrosting operation

Defrosting is required only during air heating operation when the outdoor coil 12 is operating as an evaporator. When sufficient frost has formed on the outdoor coil 12 to require the latter to be defrosted, the increased air pressure drop across the coil 12 causes the switch DCS of the defrost control DC to close. At this time, the refrigerant pressure within the coil 12 is relatively low, and the switch DLCS of the defrost limit control DLC is closed. The defrost relay DR is energized through the closed switches DCS and DLCS, and opens its switches DRS1 and DRS3, and closes its switches DRS2 and DRS4. The opening of the switch DRS1 deenergizes the fan relay OFR which opens its switch OFRS, stopping the outdoor fan motor OFM. Since there is now no air being blown over the coil 12, the defrost control DCS opens, but the now closed switch DRS2 connected across the switch DCS maintains the relay DR energized. The now open switch DRS3 deenergizes the heater resistor 30 of the time delay relay 1TDR, and the by-pass valve relay BPVR. The now deenergized relay BPVR opens its switch BPVRS2 and closes its switch BPVRS1. The now open switch BPVRS2 deenergizes the winding 3TDRW which opens its switches 3TDRS1 and 3TDRS3. The now open switch 3TDRS3 deenergizes the heater resistor 50 which cools and causes the switch 3TDRS2 to warp closed, but since the switch 3TDRS1 is now open, the by-pass valve solenoid BPVSOL cannot be energized through the closed switch 3TDRS2. The now closed switch BPVRS1 energizes the winding 2TDRW which closes its switches 2TDRS1 and 2TDRS3. The now closed switch 2TDRS1 energizes through the closed switch 2TDRS2 the by-pass valve solenoid BPVSOL which opens the by-pass valve BPV, permitting high pressure gas from the indoor coil 14 which has been operating as a condenser to flow through the by-pass tube 19 into the outdoor coil 12 which has been operating as an evaporator. The now closed switch 2TDRS3 energizes the heater resistor 40 which heats, and after a period of time, causes the switch 2TDRS2 to warp open and deenergize the solenoid BPVSOL which closes the by-pass valve BPV.

After a period of time sufficient for the by-pass valve BPV to have opened and closed as described, the switches 1TDRS1 and 1TDRS2 of the time delay relay 1TDR warp open as a result of the heater resistor 30 having been deenergized. The now open switch 1TDRS1 deenergizes the reversal valve solenoid RVSOL which adjusts the valve RV to its air cooling position. The now open switch 1TDRS1 cannot deenergize the motor starter 2MS since it is shunted by the closed switch DRS4 so that the compressor motor CM remains energized.

The outdoor coil 12 now operates as a condenser, and the heat from it melts the frost that has formed on it. When the frost on the coil 12 has melted, the pressure within the coil 12 rises and opens the switch DLCS of the defrost limit control DLC, deenergizing the defrost relay DR which opens its switches DRS2 and DRS4 and closes its switches DRS1 and DRS3. The now closed switch DRS1 energizes the fan relay OFR which closes its switch OFRS, starting the fan motor OFM. The now closed switch DRS3 energizes the heater resistor 30, and the relay BPVR. The latter closes its switch BPVRS2 and opens its switch BPVRS1. The now open switch BPVRS1 deenergizes the winding 2TDRW which opens its switches 2TDRS1 and 2TDRS3, the latter deenergizing the heater resistor 40 which cools and permits the switch 2TDRS2 to warp closed. The now closed switch

BPVRS2 energizes the winding 3TDRW which closes its switches 3TDRS1 and 3TDRS3. The now closed switch 3TDRS1 energizes the by-pass valve solenoid BPVSOL through the closed switch 3TDRS2. The solenoid BPVSOL opens the by-pass valve BPV, permitting high pressure gas from the outdoor coil 12 which has been operating as a condenser, to flow through the by-pass tube 19 into the indoor coil 14 which has been operating as an evaporator. The now closed switch 3TDRS3 energizes the heater resistor 50 which heats and after a period of time causes the switch 3TDRS2 to warp open and to deenergize the solenoid BPVSOL which closes the by-pass valve BPV.

After a period of time sufficient for the by-pass valve

BPV to have opened and then reclosed as described, the switches 1TDRS1 and 1TDRS2 are warped closed by heat from the now energized heater resistor 30. The now closed switch 1TDRS1 energizes the reversal valve solenoid which acts to adjust the reversal valve RV to its air heating position. At the same time, the closed switch 1TDRS2 energizes the motor starter 2MS which was deenergized by the opening of the switch DRS4. The heat pump is now back in indoor air heating operation under control of the heat thermostat HT.

The defrost relay could be of the slow switch opening type so that the switch DRS4 would remain closed until the switch 1TDRS2 closes, thus maintaining the compressor in operation during the change over from defrosting to indoor air heating operation.

It is seen that this invention provides that just before the reversal valve is reversed in either direction, a by-pass is opened for permitting high pressure gas from the coil which has been operating as a condenser to flow directly into the coil which has been operating as an evaporator, following which the by-pass is closed, and the reversal valve is reversed.

What is claimed is:

1. A heat pump comprising an indoor air coil, an outdoor air coil, a refrigerant compressor, reversal valve means and two-way expansion means connected in a closed refrigeration circuit, means including a first solenoid for adjusting said valve means to route refrigerant from said compressor to said outdoor coil to operate said outdoor coil as a condenser and said indoor coil as an evaporator, and for adjusting said valve means to route refrigerant from said compressor to said indoor coil to operate said indoor coil as a condenser and said outdoor coil as an evaporator, said valve means being adjusted to route refrigerant from said compressor to said outdoor coil when said solenoid is energized, and to route refrigerant from said compressor to said indoor coil when said solenoid is deenergized, a by-pass tube connecting said coils, a normally closed valve in said tube, a normally energized, second solenoid for opening said normally closed valve when said second solenoid is energized, a defrost relay having a normally closed switch, a defrost initiating control having a switch which closes when frost forms on said outdoor coil when said outdoor coil is operating as an evaporator, means including said switch of said control, when closed, in series with said defrost relay for energizing said defrost relay, a heat control thermostat having a switch which closes when said thermostat calls for heat, and means including means energized when said thermostat switch and said switch of said defrost relay are closed, for first energizing said second solenoid, for next deenergizing said second solenoid, and for next energizing said first solenoid.

2. A heat pump as claimed in claim 1 in which means including means energized when said thermostat switch opens, and when said switch of said defrost relay opens, is provided for first energizing said second solenoid, for next deenergizing said second solenoid, and for next deenergizing said first solenoid.

3. A heat pump as claimed in claim 2 in which a defrost terminating control is provided and which has a

normally closed switch which opens when frost has melted from said outdoor coil, and in which said last mentioned switch is in series with said switch of said defrost initiating control and said defrost relay.

4. A heat pump as claimed in claim 1 in which a defrost terminating control is provided and which has a normally closed switch which opens when frost has melted from said outdoor coil, and in which said last mentioned switch is in series with said switch of said defrost initiating control and said defrost relay.

5. A heat pump comprising an indoor air coil, an outdoor air coil, a refrigerant compressor and two-way expansion means connected in a closed refrigeration circuit, means including a first solenoid for adjusting said valve to a first position when said solenoid is energized, and adjusting said valve means to a second position when said solenoid is deenergized, said valve means in said first position routing refrigerant from said compressor to said outdoor coil to operate said outdoor coil as a condenser and said indoor coil as an evaporator, said valve means in said second position routing refrigerant from said compressor to said indoor coil to operate said indoor coil as a condenser and said outdoor coil as an evaporator, a by-pass tube connecting said coils, a normally closed valve in said tube, a normally deenergized, second solenoid for opening said normally closed valve when said second solenoid is energized, a defrost initiating control having a switch which closes when frost forms on said outdoor coil when said outdoor coil is operating as an evaporator, means including said switch of said control in series with said defrost relay for energizing said defrost relay when said switch of said control is closed, a heat control thermostat having a switch which closes when said thermostat calls for heat, a by-pass valve relay having a first switch which is closed and a second switch which is open when said by-pass valve relay is deenergized, first timing means having a normally open switch which closes a predetermined period of time after said timing means is energized and which opens a predetermined period of time after said timing means is deenergized, means including said thermostat switch, when closed, and

said switch, when closed, of said defrost relay for energizing said timing means and said by-pass valve relay, second timing means having a switch which closes when said second timing means is energized and then reopens after a predetermined period of time, third timing means having a switch which closes when said third timing means is energized and then reopens after a predetermined period of time, means including said open switch, when closed, of said by-pass valve relay for energizing said third timing means, means including said switch of said third timing means for energizing and deenergizing said second solenoid, means including said switch of said first timing means for energizing said first solenoid after said second solenoid has been energized and deenergized, means including said closed switch of said by-pass valve relay for energizing said second timing means, means including said switch of said second timing means for energizing and deenergizing said second solenoid, said first timing means being deenergized when said by-pass valve relay is deenergized and closes its normally closed switch, said switch of said first timing means opening and deenergizing said first solenoid after said second solenoid has been energized and deenergized by the closing and opening respectively, of said switch of said second timing means.

6. A heat pump as claimed in claim 5 in which a defrost terminating control is provided and which has a normally closed switch opens when frost has melted from said outdoor coil, and in which said last mentioned switch is in series with said switch of said initiating control and said defrost relay.
